UNITED STATES PATENT OFFICE.

CURTIS N. WILCOX, OF BROOKLYN, NEW YORK.

BLACKING-BRUSH.

SPECIFICATION forming part of Letters Patent No. 415,354, dated November 19, 1889.

Application filed August 8, 1889. Serial No. 320,124. (No model.)

To all whom it may concern:

Be it known that I, CURTIS N. WILCOX, a citizen of the United States, residing at Brooklyn, in the county of Kings, State of New York, have invented certain new and useful Improvements in Blacking-Brushes, of which the following is a specification, reference being had therein to the accompanying drawings.

10 This invention has relation to certain new and useful improvements in blacking-brushes of that class wherein is combined in one device a dauber, a polisher, and a blacking-box, the parts being so arranged that the head of 15 the dauber serves as a cover to the blacking-box.

10 The present invention has for its object to provide a simple and durable device of this class, division being made for the ready assembly 20 of all the parts and the easy inversion of the dauber to take out a quantity of blacking from the box and the quick return of the same to its normal position to cover the blacking.

25 The novelty resides in the peculiarities of construction and the combination, arrangement, and adaptation of parts, as more fully hereinafter described, shown in the drawings, and then particularly pointed out in the 30 claims.

The invention is clearly illustrated in the accompanying drawings, which, with the letters of reference marked thereon, form a part of this specification, and in which—

35 Figure 1 is a side elevation of a brush embodying my invention. Fig. 2 is a top plan of the same, and Fig. 3 is an end elevation.

Like letters refer to like parts in all the views of the drawings.

40 Referring to the drawings by letter, A designates a suitable brush-head of any approved form, to which are attached in any suitable manner the bristles B and handle B'. Attached to the head A at the end opposite the 45 handle is a metallic plate C, which has a lateral portion C' resting upon the top of the head, and to which is secured in any suitable manner the blacking-box holder D, (or it may be an integral part of said holder D,) which 50 is formed with the upwardly-extending lugs or flanges D', which are elastic or springy, and are adapted to hold the blacking-box E.

In practice, I design to so construct this holder that the said flanges will be sufficient means for holding the blacking-box; but in 55 order to adapt the holder to boxes of slightly-varying diameters I provide a set-screw D², which passes through one of said flanges, and is designed to bear against the box to hold it in a manner well understood. 60

The blacking-box is without a cover, the head of the dauber being constructed to serve this office, as will be hereinafter explained.

The plate C is formed with a vertical portion C², which at its upper end terminates in 65 an outwardly-curved or lateral portion C³. This vertical portion C² may be an extension of one of the flanges D' of the box-holder, as shown by dotted lines in Fig. 1. Near the upper end of this vertical portion I form a 70 vertical slot C⁴, which is of the form shown in Fig. 3—that is, terminating at its lower end in an enlarged portion C⁵, for a purpose hereinafter explained. This vertical portion of the plate may be formed in any desired or- 75 namental shape.

The dauber consists of a suitable head, to which are connected in any suitable manner the bristles F.

G is a preferably metallic sleeve or cylinder, preferably tapered to aid in its readily seating itself upon the blacking-box and with its smaller end embracing the head of the dauber. It is secured thereto in the following manner: H is a wire bent to form a suitable handle, and the ends thereof passed through openings or slots H' H² in diametrically-opposite sides of the cup, and centrally into the head of the dauber is the screw I, which also passes through an aperture in a 80 washer I', as shown clearly in Fig. 2, so that the screwing up of the screw binds the washer upon the arms of the wire, thus connecting the cup, wire, and dauber together. Attached to the ends of the wire H outside of the cup 85 G is the head J, which terminates in a circular portion J', between which and the main body of the head the same is reduced to form a neck or groove J².

To the upper face of the handle B' is secured a hook B², and beneath said hook the said handle is preferably formed with a transverse cut or groove B³, for a purpose herein- 100 after set forth.

In practice the parts are assembled as shown, the dauber and its attachments being connected with the brush by first inserting the head J' through the enlarged portion C⁵ 5 of the slot C⁴ in the plate C, and then bringing the handle H down to engage it with either the hook B² or groove B³ of the handle, as shown. This is the normal position of the parts. When it is desired to use the dauber, 10 the bight of the handle is disengaged from its hook or groove and the dauber turned upside down in the position in which it is shown in Fig. 3 by the simple manipulation of the handle, the neck J² working in the slot serving 15 as a trunnion on which the parts revolve, the enlarged head J' serving to prevent separation of the parts. When sufficient blacking has been obtained on the dauber, the parts are brought into their normal position, as 20 seen in Fig. 1, by the manipulation of the handle above described, and the parts locked by engagement of the bight of the handle with either its hook or groove.

By the above construction the parts are 25 readily assembled, the dauber is easily reversed, and the separation of the parts in the turning of the dauber is prevented.

What I claim is—

1. The combination, with the brush and the

plate C, attached thereto, of the dauber and 30 the handle fixed thereto, with one end connected with said plate to rotate therein and the other end detachably connected with the handle of the brush, substantially as specified.

2. The combination, with the brush and the 35 plate C, attached thereto and having a vertical portion formed with a key-hole slot, of the dauber having a handle connected thereto, and a head on said handle having an enlarged end J' and groove J² and engaging the said 40 slot, substantially as and for the purpose specified.

3. The combination, with the brush and its 45 handle formed with a groove B³, of the plate C, attached to the head of the brush and formed with a vertical portion having a key-hole slot, the dauber provided with a cup, the wire handle attached to the dauber, and the head in the handle formed with an enlarged end J' and neck J², working in the slot of said 50 plate, substantially as specified.

In testimony whereof I affix my signature in presence of two witnesses.

CURTIS N. WILCOX.
